UNITED STATES PATENT OFFICE.

FAIRLEIGH S. DICKINSON, OF BAYONNE, NEW JERSEY.

DESIGN FOR A BOX FOR HYPODERMIC NEEDLES.

SPECIFICATION forming part of Design No. 34,024, dated February 5, 1901.

Application filed January 12, 1901. Serial No. 43,082. Term of patent 7 years.

To all whom it may concern:

Be it known that I, FAIRLEIGH S. DICKINSON, a citizen of the United States, and a resident of Bayonne, in the county of Hudson and State of New Jersey, have invented and produced a new and original Design for a Box for Hypodermic Needles, of which the following is a specification, reference being had to the accompanying drawings, forming a part thereof, in which—

Figure 1 is a perspective view of a box embodying the features of my design, and Fig. 2 is a section taken on the line 2 2 of Fig. 1.

The leading features of the design consist in a tray-body A and an arched bridge B within the tray-body, in which bridge are a series of elongated openings C.

The minor features of the design consist in the formation of the bridge, in which the ends of the bridge curve toward the bottom and

ends of the box, the top of the bridge being flat, and in the oblong shape of the openings and their location, the openings appearing partially in the ends of the bridge and in that portion of the body adjacent to the ends, together with recesses D, which appear at one side portion of the bridge. 25

Having thus described my invention, I claim as new and desire to secure by Letters Patent—

The design for a box for hypodermic needles herein shown and described. 30

In testimony whereof I have signed my name to this specification in the presence of two subscribing witnesses.

FAIRLEIGH S. DICKINSON.
